UNITED STATES PATENT OFFICE.

RUSSELL E. TUPPER, OF SANDWICH, MASSACHUSETTS.

SCREEN-DOOR FASTENER.

960,445.

Specification of Letters Patent. Patented June 7, 1910.

Application filed September 22, 1909. Serial No. 518,921.

To all whom it may concern:

Be it known that I, RUSSELL E. TUPPER, a citizen of the United States, residing at Sandwich, in the county of Barnstable and State of Massachusetts, have invented new and useful Improvements in Screen-Door Fasteners, of which the following is a specification.

The invention relates to an improvement in checks and fastenings for doors, being particularly directed to a device designed particularly for use with screen doors and the like and adapted to check the closing action of the door and to secure the door in closed position.

The main object of the present invention is the provision of a check and door fastener, including a catch element to be secured to the door and a buffer element to be secured to the casing, the respective parts being so constructed as to retard the closing action of the door, during the riding contact of said parts, and finally interlock to provide a fastening means for securing the door in closed position.

The invention in its preferred form of details will be described in the following specification, reference being had particularly to the accompanying drawings, in which:—

Figure 1 is a broken perspective illustrating the application of the improved checking fastener. Fig. 2 is an elevation of the fastener with the parts thereof in separated relation.

Referring to the accompanying drawings, the improved fastening comprises a catch element 1 and a buffer element 2, the former being designed to be secured to the door and the latter to the door frame or casing.

The catch element includes a strip of approximately flat material which, at one end, is bent at right angles to the main length of the strip, as at 3, to provide an extension by which the catch member, through the

medium of screws or other fastenings, may be secured to the door. The main length 4 of the strip projects at right angles from the section 3 and is terminally provided with a head 5 of approximately diamond shape in elevation.

The head is of a width corresponding to the width of the strip, and is of somewhat greater length in alinement with the strip than in its transverse dimension. The angularly related upper and lower edges 6 and 7 of the forward portion of the head are at a less angle to each other and to the

longitudinal line of the head than the rear angularly related edges 8 and 9. By this construction, the incline of the edges 6 and 7, from the forward point of the head, is less, or more gradual, than the incline of the rear edges 8 and 9, from the rear end of the head.

The buffer element 2 is shaped in approximate correspondence with the shape of the head 5, but reversely arranged, that is the forward upper and lower edges 10 and 11 are at a greater incline with respect to the longitudinal median line than the rear upper and lower edges 12 and 13.

The contact element is secured to the door 14 so that the head projects in advance of the inner surface of the door, and the catch element is secured to the casing 15, through the medium of screws or other fastenings, so that its longitudinal median line is parallel with and slightly below the angular position of the longitudinal median line of the head 5. In other words, the forward point of the head 5 is, in the normal position of the parts, slightly above the rear point of the buffer element. The buffer is so spaced, with relation to the door length edge of the casing, that the head 5 will over-ride said buffer element when the door is in closed position, and in such closing it will be noted that the forward portion of the edge 7 of the head will engage and ride upon the rear upper edge 12 of the buffer element, the movement continuing until the lowest point of the head, that is the juncture between the edges 7 and 9, will ride over the juncture between the upper edges 10 and 12 of the buffer element. Immediately succeeding this point, the rear lower edge 9 of the head rides upon and into contact with the forward edge 10 of the element, and as these edges have the identical angular inclination, they will contact particularly throughout their lengths and thereby secure the door against accidental opening.

It is understood, of course, that the main length 4 of the catch element is of spring type, and of sufficient strength to insure operative contact of the head and buffer in the operation, it being noted that as the result of this arrangement the initial riding of the head upon the buffer element tends to elevate the head, which is restricted by the tension of the main length 4 of the strip, with the effect of retarding or checking the closing action, said spring exerting sufficient

tension, when the edges 9 and 10 of the head and buffer are in contact, to prevent accidental separation of such parts and thereby maintain the door in closed position.

5 The catch element is preferably of metallic structure, while the buffer element is preferably of resilient or deadening material, as rubber or the like, whereby the contact between the head and buffer is noiseless, 10 checking the door without sound. Both the catch member and the buffer are reversible, so that wear on any one portion, caused by continued use, may be remedied by reversing the parts. I contemplate the use of any material 15 in constructing either element, preferring, however, the use of metal for the catch element and rubber for the buffer element.

Claims.

20 1. A door check and fastener including a catch element and a buffer element, the catch element including a spring strip adapted to be secured at one end to the door and a head secured upon the strip and having its lower

edge formed to provide two divergent angularly related surfaces, the buffer element having its upper edge formed with similar surfaces, the respective surfaces of the edge of each element being of different lengths and at different angles to the horizontal. 25

2. A door check and fastener including a catch element having spring connection with the door and a buffer element having fixed connection with the door casing, said catch element and buffer element each comprising 30 approximately diamond shaped bodies having their upper and lower edges presenting two divergent angularly related surfaces, the initial engaging surfaces of the elements being at less inclination to the horizontal than 35 the finally engaging surfaces of the elements. 40

In testimony whereof I affix my signature in presence of two witnesses.

RUSSELL E. TUPPER.
